UNITED STATES PATENT OFFICE.

ZYGMUNT SLAWINSKI, OF SOUTH PLAINFIELD, NEW JERSEY.

SAFETY DOOR FOR FREIGHT CARS.

1,406,095.

Specification of Letters Patent. Patented Feb. 7, 1922.

Application filed October 25, 1920. Serial No. 419,196.

To all whom it may concern:

Be it known that I, ZYGMUNT SLAWINSKI, a citizen of Poland, and resident of South Plainfield, in the county of Middlesex and 5 State of New Jersey, have invented certain new and useful Improvements in Safety Doors for Freight Cars, of which the following is a specification.

The main object of this invention is the 10 provision of a safety lock for freight car doors, in order to prevent the numerous and frequent thefts prevalent in railroad yards and on side tracks owing to the failure of the locks at present used to defy the manipulations of burglars.

The above and other objects will become apparent in the description below, in which like characters of reference refer to like-named parts in the drawings.

20 Referring briefly to the drawings, Fig. 1 is a perspective view of a freight car, illustrating the application of my lock.

Fig. 2 is a diagrammatic, fragmentary side elevational view of a portion of said car, illustrating the means of opening the door lock of said car.

Fig. 3 is an enlarged detail view of the operating mechanism of my lock, the latter being in closed position.

25 Fig. 4 is a cross-sectional view taken on the line 4—4 of Fig. 3.

Fig. 5 is a cross-sectional view taken on the line 5—5 of Fig. 3.

30 Fig. 6 is an enlarged detail view of the operating mechanism of my lock, the latter being in open position.

Referring now in detail to the drawings, the numeral 1 represents the side walls of a freight car and 2 the entrance to the interior

40 thereof, in which the door 3 is slidably mounted on a runway 35. A plate 4 is attached to the door 3 as shown, and an upwardly pointing hooked member 5 is rigid with the upper end of said plate, while a

45 T-shaped member 7 is rigid with the lower end of said plate, both of said members extending beyond the edge of the door. The hook 5 provides a recess 6, and the T-shaped member 7 provides recesses 8 and 9. A

50 supporting plate 10 is attached to the car wall adjacent the doorway, and a bearing plate 11 is mounted upon pins 11^a spaced parallel to the plate 10. Spaced apart pins 12 extend between said plates 10 and 11 and

55 provide pivots for the support of levers 19 having converging hooked ends 20 adapted

to engage the member 7 in the recesses 8 and 9. A pin or shaft 13, having a squared portion 13^a extending beyond the outside of the car wall, is pivotally mounted between the 60 plates 10 and 11, and a link 14 is rigidly attached thereto. A plate 21 is attached by means of pins 21^a to the plate 10, at a distance therefrom, and a substantially elliptical cam 18 is pivotally mounted at 17 between 65 said plates. A link 16 is rigidly attached to said cam, and connected through another link 15 to the link 14.

A guide bar 22 limits the outward lateral movement of the levers 19. A coiled spring 70 23 is attached to both levers 19 and tends to draw them together. A vertical rod 25 is slidably mounted in recesses provided in a pair of horizontal guides 26, the lower extremity of said rod being curved in the form 75 of a hook and engaging a hole 24 in the upper lever 19. A member 28 is rigid with said rod, and is pointed at the lower end at 29, said end being adapted to engage the hook 5 in the recess 6.

With the parts in the relative positions shown in Fig. 3, the door being locked, the same may be opened if the shaft 13 is rotated in a counter-clockwise direction, for the cam 18 will then cause the levers 19 to 80 separate, withdrawing the lever ends 20 from the recesses 8 and 9, and at the same time withdrawing the member 29 from the recess 6. Therefore the door 3 may be withdrawn, the parts being then in the relative positions shown in Fig. 6.

85 A key having a socket adapted to grip the squared end 13^a of the shaft 13 may be used to turn the shaft, and I have provided additional security to the lock by having a 90 cover 31 pivotally mounted adjacent the keyhole 30 and adapted to be swung into position to conceal the hole 30. A thumb screw 33 may be screwed into a recess 34 and thereby retain the cover in locked position.

100 I claim:

1. A lock for sliding doors comprising a two armed keeper having recessed arms, a lock plate, a pair of opposed levers pivoted thereon, said levers being engageable with the recesses of one arm, a detent operable by one of said levers engageable with the recess of the other arm, a spring drawing said levers towards each other, a cam journaled 105 on said plate between said levers, a lever for actuating said cam, a key operated lever 110

remote from the last named lever, a link connecting said cam and key levers, and an obscuring shutter normally covering the entrance to said key lever.

- 5 2. A lock for sliding doors comprising a keeper plate attached to the door, a pair of offset arms extending beyond the edge of the door, said arms being in a vertical plane, a recess in the upper of said arms open at 10 its upper edge, recesses in both edges of the lower arm, a plate on the wall adjacent the door, a pair of levers pivoted to said plate, said lever having inturned ends engageable in the recesses of said lower arm, spring con-

straining means for said levers, a cam between said levers rotatably mounted in the last named plate, a vertically slideable detent mounted on the wall engageable in the recess of said upper arm, connections between one of said levers and said detent, and key operated means for actuating said cam, said means being at a point remote from the axis of the cam.

Signed at New York, in the county of New York and State of New York, this 11th 25 day of October, A. D. 1920.

ZYGMUNT SLAWINSKI.
